UNITED STATES PATENT OFFICE.

CHARLES S. WEEKS, OF BROOKLYN, AND HENRY R. EVANS, OF NEW YORK, N. Y.,
ASSIGNORS TO KELLEY TICKET MACHINE COMPANY, OF NEW YORK, N. Y., A COR-
PORATION OF NEW YORK.

COIN-TESTING MECHANISM FOR VENDING-MACHINES.

1,200,059.

Specification of Letters Patent.

Patented Oct. 3, 1916.

Application filed November 6, 1913. Serial No. 799,459.

To all whom it may concern:

Be it known that we, CHARLES S. WEEKS, a citizen of the United States, residing in the borough of Brooklyn, county of Kings, and State of New York, and HENRY R. EVANS, a citizen of the United States, residing in the borough of Manhattan, city, county, and State of New York, have invented a new and useful Improvement in Coin-Testing Mechanisms for Vending-Machines, of which the following is a description.

This invention relates to vending machines of the coin-controlled type, and particularly relates to testing mechanism for such machines.

Primarily, it should be noted that the mechanism of our present invention has been designed with reference to coin-controlled apparatus for vending tickets or other flat articles in web form wound in reels or stacked in flat form, the length of the stack being preferably the length of five or more articles or tickets of the web.

Among the objects of our invention may be noted the following: to provide, in a check-controlled apparatus, a means for testing the material of which said check is made in order to throw out a spurious coin; to provide a material testing device which will prevent the mechanism, through which the device operates, from performing a functional operation except when a coin of the proper denomination is inserted in the machine; to provide testing apparatus which makes it impossible for the machine, with which it is incorporated, to perform its operation with anything other than a good coin of the proper denomination; to provide an apparatus for coin-controlled machines which will reject slugs, disks, rings, washers and other things in form similar to a coin; to provide means under control, so that but one coin at a time can effect the delivery of a ticket or article to be vended from the machine; to provide means which will insure the retention of a good coin placed in the machine and prevent it from being recovered by the vendee; to provide a material-testing apparatus in a normally open electrical circuit, operated by the insertion of a coin in the apparatus which will close the circuit and start the apparatus into operation; to provide a testing apparatus, irrespective of how driven, with a unit mechanism ca-

pable of use for single checks or coins, and capable of multiplication to any desired extent to produce a gang-machine operable by any number of coins or checks of any predetermined value or character; to provide a testing mechanism capable of automatically discriminating between a good coin of the proper denomination, and any other form of check, so as to start the machine, with which the testing mechanism is combined, into operation for the good coin, and prevent the operation of said machine in the presence of the other form of check; and to provide novel elements and mechanisms, and combinations of mechanisms and elements operating automatically to produce functions according to a given rule of action imposed thereon by the coins or checks inserted in the machine, and constituting the initial control and impulse.

With the above objects in view and others which will be detailed during the course of this description, our invention consists of the elements, mechanisms, and features, and combinations of elements and mechanisms as hereinafter described and claimed.

In order that our invention may be clearly understood we have provided drawings, wherein:

Figure 1 is a front elevation taken at an angle of 30° to the horizontal, of much of a vending machine as is deemed necessary to illustrate the application of our invention, a part of the casing being broken away to show the coin testing mechanism; Fig. 2 is a side elevation of the mechanism shown in Fig. 1, the view being toward the left of said figure; Fig. 3 is a top plan view of Fig. 2, taken at 30° from the perpendicular; Fig. 4 is a front elevation of the mechanism shown in Fig. 1, and at the same angle to the horizontal, the parts being illustrated in a different position; Fig. 5 is a sectional view taken substantially on the line 5—5, Fig. 4, looking in the direction of the arrow; Fig. 6 is a sectional detail on the line 6—6, Fig. 7, looking in the direction of the arrow; and Fig. 7 is a sectional view of Fig. 6, taken on the line 7—7, Fig. 6, looking in the direction of the arrows and showing the coin caliper device.

In the drawings, the back and front plates of the casing of the machine, to which this

testing mechanism is attached and forms a part, are fragmentarily shown at 1, and a fragment of the front plate of the machine is illustrated at 2. Coin slots 3, 4 and 5 are 5 provided and, for convenience of manufacture, are constructed in two halves of metal insulated from the front plate 2 in any suitable manner, one method of insulating the same being shown at 6.

10 Each testing device consists primarily of a frame 7, secured to a ledge or plate 8, forming a part of the machine to which said testing device is attached. Said frame 7 can be secured to the ledge 8 in any suitable 15 manner, and as shown in the drawing, is secured thereto by screws 9. The halves 10 and 11, forming the coin-slot plate, are secured to brackets 12 and 13 of the frame 7 in any suitable manner, as by rivets 14, said 20 plates 10 and 11 being insulated from said arms by fiber bushings 15.

When a coin is introduced into one of the coin-slots, reference being had to Fig. 2 of the drawings wherein the coin is illustrated 25 at 16, said coin contacts on two metallic members or rolls 17 and 18. The plug 17 is mounted on an insulating arm 19, mounted in a lever 20, said lever and arm being pivotally mounted at 21, Fig. 5, to a boss 30 or hub 22, forming a part of the frame 7. The plug 18 is secured on an insulating arm 23 carried in a lever 24, said arm and lever being pivotally mounted at 25 on a boss 26 forming a portion of the frame 7, and said 35 insulating block 23 and lever 24 forming a bell-crank, the lever 24 being bifurcated at its end 27, and having a pin 28 secured therein transverse of said bifurcation to co-operate with a slot 29 formed in a projection 40 of the lever 20. Reference being had to the drawings, and more particularly to Fig. 5 thereof, it can be clearly seen that any rotation of the plug 17 about the pivot 21 will cause a similar rotation of the plug 18 45 about the pivot 25 in an opposite direction, and vice versa. The object of the plugs 17 and 18 is to form an electrical switch co-operating with a coin and, carrying out this idea, terminals 31 and 32 are secured to the 50 blocks 19 and 23, respectively, and are held thereto by a turned down portion of the plugs 17 and 18 passing through the fiber blocks 19 and 23 and being riveted over toe-pieces formed on said terminals 31 and 32.

55 It is evident that to make good contact between the plugs 17 and 18 with a coin, said plugs must be held yieldingly toward each other, and require pressure to separate them a sufficient distance to allow for the 60 passage of a coin between them. To secure such necessary yielding pressure, a block 33 is pivotally mounted at 34 to the frame 7, said block 33 being provided with a stem 35 passing through an aperture in a right-angle projection 36 of the lever 20, a spring 65

37 being interposed between said turned down portion 36 and the block 33. It is evident that if the plugs 17 and 18 are forced apart the spring 37 will be compressed and upon the passage of the coin 70 past its greatest diameter, said spring 37, through the lever 20, arm 19, pin 28, slot 29, lever 24, and arm 23, will force the plugs 17 and 18 toward each other to their initial position, such movement being limited by a 75 stop 38 secured to the frame 7, and will give to the coin an impulse in the direction of introduction.

Secured to a portion of the frame 7 is a Z-shaped bracket 39 of non-magnetic material, held to said frame 7 by screws 40, or in any other suitable manner. An electromagnet 41 is mounted on the up-standing member 42 of said bracket 39, by having a portion of the core 43 pass through said 80 bracket 39, and a fiber block 44, and having a nut 45 at its free end. Said fiber, or other insulating block 44, is provided with three terminals 46, 47, and 48, said terminals being double; that is, having portions above 90 and below the insulating block 44. From the terminal 31 a flexible lead 31^a is carried to the lower end of the terminal 46, and from the terminal 32 a flexible lead 32^a is carried to the lower end of the terminal 47, 95 one end of the winding of the electromagnet 41 being attached to the upper end of the terminal 47, a lead 46^a being taken from the upper end of the terminal 46 to a source of electromotive force, the other end 100 of the winding on the electromagnet 41 being secured to the lower end of the terminal 48, and a lead 48^a being taken from the upper end of the terminal 48 to the opposite pole of the source of electromotive force. 105 Upon the introduction of a coin between the plugs 17 and 18, the circuit is closed and the core 43 of the electromagnet 41 is energized. The function of this electromagnet will be fully described later. 110

To the frame 7 are secured by means of screws 49, or any other suitable manner, U-shaped brackets 50 and 51, having unequal legs, said brackets carrying on their free end a plate 52 secured thereto by screws 115 53. Secured to said plate 52 is a horse-shoe magnet 54 of some high magnetic material, preferably tungsten steel, the securing means for said magnet being shown as ears 55 punched up out of the plate 52 and bent 120 over the magnet. The Norway iron poles 56 and 57 of said magnet are shown as being riveted into the ends of said magnet at right angles to the plane thereof. It is essential, to prevent leakage of magnetic lines from the 125 magnet 54, that the plate 52 be of some non-magnetic material, such as brass or the like.

Secured to the brackets 50 and 51, in any suitable manner, and as illustrated by screws 58, are bearing blocks 59 and 60, of insulat- 130

ing material, in which are mounted a rod or shaft 61. Mounted on said rod 61 is a U-shaped hanger 62 having eyes 63 formed on the ends thereof, and adapted to coöperate with the rod 61 and swing therewith. Mounted on the rod 61 is a plate 64 bent into an inverted U-form at 65 to partly encircle the rod 61 and to straddle the hanger 62 and which is rigidly secured thereto by the Swedish iron bolt 67 having the disk-shaped head 66 and nut 68. Any movement of the said bolt 67 about the axis 61 is directly imparted to the U-shaped hanger 62 and the plate 64 with which, through the U-shaped mounting 65, it forms an integral part. The plate 64 has two ears 89 and 90 encircling the bar of hanger 62 and rigidly secured thereby by soldering, or in some other suitable manner. Rigidly secured to the plate 64 in a predetermined relation thereto is a hook-shaped arm 70, the function of which will later be described. A portion of the downwardly extending plate 64 is bent into a toe-shaped ledge 71 which forms with a ledge 72 on a plate 73, a continuous run-way, under certain conditions, for a coin. Said plate 73 is pivotally mounted at 74 to the bar of the hanger 62, and is free to swing thereon under control of a link 75 pivoted to a lug or ear 76 punched up out of said plate 73, and to a pin 77, carried in an insulated bearing block 78, secured to the bottom of plate 52 by rivets 79, or in any other suitable manner. Encircling the rod or shaft 61 is a spring 80, one end of which bears against a projection of the bearing block 59, and the other end bearing against the bar of the U-shaped hanger 62, and holding the same normally in the position shown in Fig. 4 of the drawings.

The functions and operation of the above described mechanism are as follows: Upon the introduction of a coin in the slot 5, for example, said coin engages the plugs 17 and 18, and by being forced therethrough establishes a good electrical connection therewith, which closes the circuit between the electromagnet 41 and a source of electromotive force, and thereby energizes the core 43 of said magnet, whereupon the disk 66 is attracted and the plate 64 and its appurtenances are drawn over into the position shown in Fig. 1 of the drawings. The coin then passes along the ledge 71 and by the side of said plate 64 adjacent to the hook 70 secured thereon, and after the greater diameter of the coin has passed between the bite or nip of the plugs 17 and 18, it is forced inwardly, owing to the tendency of said plugs to approach closer to each other under the impulse of the spring 37 and the connecting joints and levers. Just as the coin passes out of contact with the plugs 17 and 18, its motion is arrested by an abutment 81 bent up from a plate 82, in Fig. 5,

adjustably secured in a slide-way 83 on the frame 7 of the device, by a screw 84, the plate 82 having an elongated slot 85 for that purpose. As the circuit between the source of electromotive force and the magnet 41 is now broken, the core 43 of said magnet loses its magnetic energy and the U-shaped hanger 62 and the plate 64 and its appurtenances are thrown into the position illustrated in Fig. 4 of the drawings, under the impulse of the spring 80. The coin then clears the abutment 81 and, if it be a good one and of the proper denomination, rolls by gravity along the ledge 71 of the plate 64 and the ledge 72 of the plate 73, and into the operating mechanism of the machine to which latter this device is attached.

If the object introduced into the slot 5 were a washer of electro-conductive material, the magnet 41 would be energized, and upon the breaking of the circuit, the U-shaped hanger 62, and the plate 64, would be rapidly moved into the position shown in Fig. 4 of the drawings, but the washer would be impaled on the hook 70 and said implement would allow the lower edge of the washer to slip over the edge of the ledge 71, and so remain until the beginning of another cycle, when it would fall into a receptacle provided for that purpose, or into the body of the casing of the machine.

If the object introduced into the slot 5 of the machine is a non-metallic substance, such as a fiber, or rubber, or card-board disk, it will pass between the plugs 17 and 18, and as no closing of the circuit can take place, due to the non-conductivity of such disk, it will fall directly into said receptacle, or into the body of the casing of the machine.

If the check or object entered through the slot 5 meets the requirements of conductivity and passes the test for washers or the like, and starts on its path toward the operating mechanism of which this device forms a part, yet is thinner than a coin of the proper denomination, it will slip through the slot 86, formed in the ledge 72, of the plate 73, and drop into a receptacle provided for that purpose. See *a*, Fig. 7.

If a check or object, introduced into the slot 5, meets the requirements of conductivity and passes the test for a washer or the like, but is smaller in diameter than a coin of the proper denomination, said check or object will fall through the opening 87 in the plate 64 and drop into a receptacle provided for that purpose, or into a chute which would return it to the outside of the machine. See *b*, Fig. 7.

If a check or object, introduced into the slot 5, passes the test of conductivity and the test for a washer or the like, and is of some material readily attracted by a magnet, such as iron, steel or the like, it will come in contact with the terminals 56 and 57

of the horseshoe magnet 54, a slot 88 being provided in the plate 73 for that purpose, whereupon its course will be arrested and it will be held in that position with its edge 5 resting upon the ledge 71 of the plate 64, whereupon at the beginning of another cycle, or the introduction of another coin, and the movement of the plate 64 from the position illustrated in Fig. 4 of the drawings to that 10 illustrated in Fig. 1, said magnetic disk will be stripped away from said magnetic terminals 56 and 57, by the movements of plate 73—the magnet 54 being of insufficient strength to support such disk or check except when in actual contact,—and will drop 15 into the body of the machine.

It is evident from the above description of the mechanism and description of the functional operation and arrangement of 20 parts that this device will test and eliminate washers, rings and the like; also disks of electrically non-conductive or of magnetic material; that it will test for the thickness of a coin or check; and that it will test, for 25 the diameter of a coin or check, any disk or coin of greater thickness or diameter than the coins for which the device is designed being unable to enter the slot 5, this being the initial test. It should also be noted, at 30 this point, that the extension of the lever 20, as shown in Figs. 1 to 5, inclusive, is for the purpose of coöperating with connections and establishing a connection between the coin-testing mechanism and a locking-device in 35 the vending machine for the purpose of actuating said locking-device for each movement of the said lever 20; that is to say, in the vending machine, a device is provided by means of which the other coin-receiving 40 devices are locked from operation when one of said devices is set in operation by a check passing between the lugs 17 and 18, and the lever 20 is the element of the testing mechanism which helps to establish connection 45 between the latter and the locking means in the vending machine. The said locking means has not been illustrated nor particularly described herein, as the same forms no part of our present invention.

50 Having thus described our invention, what we claim and desire to secure by Letters Patent is:

1. A coin-testing mechanism for vending machines comprising a pair of movable electrically conducting members between which the coin is entered; and electrically controlled mechanism for receiving the coin after passing said members, comprising a plurality of means for subjecting the coin 55 to a plurality of different tests.

2. A coin-testing mechanism for vending machines comprising a plurality of movable electrically conducting members between which the coin is entered; devices constituting 60 an open electric circuit in which said

members are included and mechanism for receiving the coin after passing said members, comprising a plurality of means for subjecting the coin to various different tests.

3. A coin-testing mechanism for vending 70 machines comprising movable electrically conducting means to be actuated by a coin; receiving means for taking the coin after passing the movable means; and a device coöperating with the receiving means forming 75 a connection to a locking mechanism in the vending machine, whereby said device and the locking connection may be set in action upon the acceptance of the coin by the receiving means.

4. A coin-testing mechanism for vending machines comprising a supporting-frame structure provided with a face-plate having a slot through which the coin may be passed; movable electrically conducting 85 members arranged adjacent the face-plate between which the coin passes after passing through the face-plate; and a receiving mechanism for the coin for taking the latter after passing the movable members, includ- 90 ing a plurality of devices for subjecting the coin to several different tests.

5. A coin-testing mechanism for vending machines comprising a plurality of movable electrically conducting members between 95 which the coin passes upon entering the machine; a pivotally-supported coin-receiving device normally held out of coöperative relation with the said members; means for moving the coin-receiving device into coöpera- 100 tive relation with the said members when the latter are moved by the entry of a coin; and means carried by said coin-receiving device for subjecting the coin to a pre- 105 determined test.

6. A coin-testing mechanism for vending machines comprising a plurality of spring-pressed movable electrically conducting members between which the coin passes; a coin-receiving device movably mounted so as to be capable of moving into and out of coöperative relation with said movable members; means for normally holding said device out of such coöperative relation; and magnetic means for moving said device into 115 such coöperative relation.

7. A coin-testing mechanism for vending machines embracing movable electrically conducting means operably connected with electro-magnetic means for controlling the direction of movement of the coin; and mechanically connected with means for determining its disposition within the mechanism, together with magnetically-controlled means for determining its further disposition dependent upon whether the coin inserted is the proper coin the machine should receive or not.

8. A coin-testing mechanism for vending machines embracing a plurality of movable 130

conducting members, electrically connected with electro-magnetic controlling mechanism and mechanically connected with each other in such manner as to impel the coin 5 after it passes between the movable members, in combination with mechanism for mechanically determining the ultimate disposition of the coin as it advances, and additional means for further determining this 10 condition when the coin inserted is non-magnetic.

9. A coin-testing mechanism for vending machines embracing electro-magnetically controlled means operably connected with 15 mechanically controlled mechanism which

determines whether the coin is of proper weight, and additional means which determines whether it is of proper thickness, together with magnetic means which acts to reject the coin if the same is of magnetic material. 20

In testimony whereof we have hereunto signed our names in the presence of two subscribing witnesses.
